US00D630158S

(12) **United States Design Patent**
Jessie, Jr.

(10) **Patent No.:** **US D630,158 S**
(45) **Date of Patent:** **** Jan. 4, 2011**

(54) **CHILD VEHICLE**

(75) Inventor: **Donald K. Jessie, Jr.**, Middletown, OH
(US)

(73) Assignee: **Huffy Corporation**, Centerville, OH
(US)

(**) Term: **14 Years**

(21) Appl. No.: **29/355,897**

(22) Filed: **Feb. 16, 2010**

(51) **LOC (9) Cl.** **21-01**

(52) **U.S. Cl.** **D12/423; D21/435**

(58) **Field of Classification Search** **D21/419, D21/421, 423-428, 431-435, 548; D12/107, D12/112, 129, 130, 133; 180/65.1; 280/7.1, 280/7.11, 7.15, 7.17, 47.17, 47.25, 47.38, 280/47.34, 87.01, 87.021, 87.05, 87.051, 280/282, 827, 828; 446/440**

See application file for complete search history.

(57) **CLAIM**

The ornamental design for a child vehicle, as shown and described.

DESCRIPTION

FIG. 1 is a perspective view of my new, original and ornamental design;

FIG. 2 is a rear perspective view thereof;

FIG. 3 is a front view thereof;

FIG. 4 is a right side view thereof, the left side view being a mirror image thereof;

FIG. 5 is a rear view thereof;

FIG. 6 is a top view thereof; and,

FIG. 7 is a bottom view thereof.

The phantom lines of the child vehicle are directed to environment and are for illustrative purposes only. The phantom lines form no part of the claimed design. Additionally, the unshown portion of the child vehicle forms no part of the claimed design.
